COILED WIRE HOLDER

Kenneth C. Jenne and George F. Manion, Lake
Worth, Fla.

Application June 2, 1939, Serial No. 277,098

3 Claims. (Cl. 242—129)

This invention relates to a holder for paying out heavy gage wire, such as used for guy wires and which is sold in rolled or coiled form and is extremely difficult to handle and control when released of its ties and the primary object of this invention is the provision of a device for receiving the wire in its rolled or coiled form and to retain said wire in said form when the ties thereof are released and which will permit the wire to be conveniently payed out as needed without the danger of the wire becoming entangled.

With these and other objects in view, the invention consists in certain novel features of construction, combination and arrangement of parts to be hereinafter more fully described and claimed.

For a complete understanding of our invention, reference is to be had to the following description and accompanying drawings, in which

Figure 1 is a top plan view illustrating a holder constructed in accordance with our invention.

Figure 2 is a bottom plan view illustrating the same.

Figure 3 is a sectional view taken on the line 3—3 of Figure 2.

Figure 4 is an enlarged fragmentary sectional view illustrating one of the connecting straps showing one end as being hingedly mounted and its opposite end detachably connected to one of the annular members of the holder.

Referring in detail to the drawings, the numeral 5 indicates as an entirety a holder composed primarily of superimposed annular members 6 and 7. The annular member 7 is of a larger diameter than the diameter of the member 6. The members 6 and 7 are connected together and in spaced relation to each other by substantially U-shaped straps 8 spaced an equal distance apart, as shown in Figures 1 and 2 of the drawings. The substantially U-shaped straps extend outwardly of the annular members.

One of the substantially U-shaped straps 8 has one end thereof journaled on the annular member 7 while its opposite end is slotted, as shown at 9, to receive therein a bolt 10 carried by the annular member 6 and on which is threaded a wing nut 11. The wing nut 11 permits the latter-named strap to be detached from the annular member 6 for the purpose of swinging said latter-named strap on the annular member 7 to permit placing within the space between and also within the other straps a coiled or rolled wire (not shown). The movable or hinged strap after the placing of the wire within the device is brought into engagement with the bolt and tight-

ly secured on the annular member 6 by the wing nut. Thus it will be seen that the wire will then be confined within the annular members 6 and 7 and the straps so that the usual ties employed for holding the wire in rolled or coiled form may be released whence the wire expands against the straps and thereby becomes confined within the annular members and said straps. One end of the coiled wire may be then brought through the annular member 7 and payed out, without danger of tangling, to a desired length whence it may be cut off. The free ends of the wire are normally held by being inserted through any one of a series of rings 12 mounted on the annular members 6 and 7 to prevent said ends from catching into objects during the moving of the device from one place to another. When the wire is confined within the device it can be easily carried from one place to another and as before stated, can be payed out as needed without danger of tangling and with a minimum expenditure of manual effort.

It is believed that the foregoing description, when taken in connection with the drawings will fully set forth the construction and advantages of this invention to those skilled in the art to which such a device relates, so that further detailed description will not be required.

What is claimed is:

1. A holder for a coil of wire comprising a pair of ring members of relatively different sizes and smaller in diameter than the outside diameter of the coil for confining said coil therebetween, and a plurality of yokes connected to said ring members in laterally spaced concentric relation and spaced apart equidistantly around said members, said yokes being outwardly bowed to span the coil transversely.

2. A holder for a coil of wire comprising a pair of ring members of relatively different sizes and smaller in diameter than the outside diameter of the coil for confining said coil therebetween, and a plurality of yokes connected to said ring members in laterally spaced concentric relation and spaced apart equidistantly around said members, said yokes being outwardly bowed to span the coil transversely, one of said yokes being hinged to one of said members and detachably connected to the other member for outward swinging to permit insertion of the coil between said members.

3. A holder for a coil of wire comprising a pair of ring members of relatively different sizes and smaller in diameter than the outside diameter of the coil for confining said coil therebetween, and

- a plurality of yokes connected to said ring members in laterally spaced concentric relation and spaced apart equidistantly around said members, said yokes being outwardly bowed to span the coil
5 transversely, one of said yokes being hinged to one of said members and detachably connected

to the other member for outward swinging to permit insertion of the coil between said members, and fastening elements for the ends of said coil mounted on said ring members, respectively.

KENNETH C. JENNE.
GEORGE F. MANION.
